UNITED STATES PATENT OFFICE.

GEORGE W. SHIEBLER, OF BROOKLYN, NEW YORK.

DESIGN FOR A HANDLE FOR SPOONS OR FORKS.

SPECIFICATION forming part of Design No. 22,149, dated January 24, 1893.

Application filed September 30, 1892. Serial No. 447,453. Term of patent 7 years.

To all whom it may concern:

Be it known that I, GEORGE W. SHIEBLER, a citizen of the United States, residing at Brooklyn, in the county of Kings and State of New York, have invented a Design for Handles for Spoons or Forks, of which the following is a specification, reference being had to the accompanying drawings, in which—

Figure 1 is a view of my design showing the obverse side, and Fig. 2 is a similar view showing the reverse side.

The leading feature of this design for a handle is the design of the row of globular or pearl shaped ornaments upon each extreme edge of the handle, said globular ornaments being visible from both sides of the handle and larger at the central portions than toward the ends of the rows. This globular or pearl shaped ornamentation is disposed in the rows *a. a'*. These rows *a. a'*, are upon the extreme edges of the handle and the globular or pearl shaped ornamentation tapers gradually from the larger central portions toward the respective ends. The faces of the handle upon the obverse and reverse sides within the globular

or pearl shaped edges are plain. The handle extremity is surmounted by an ornamentation in feathers, bands and globular forms representing a coronet. This ornamentation comprises an ornamental band *b*, globular ornaments *c c'* radially disposed from the band outwardly, and intermediate feather ornaments *e e' e²* with curled tips, and at the base of these ornamental portions is disposed an intertwined ribbon scroll.

The obverse and reverse sides of my design are similar as shown in the figures of the drawings, saving that the tips of the feather ornamentation bend over or curl upon the obverse side.

What I claim is:

The design for the handle for spoons, substantially as shown and described.

Signed by me this 23d day of September, 1892.

GEO. W. SHIEBLER.
